(21) Appl. No.: **29/172,632**

(57) **CLAIM**

(22) Filed: **Dec. 16, 2002**

I claim the ornamental design for a between rounds absor-
bent mat for boxing ring, as shown and described.

(51) LOC (8) Cl. **06-11**

DESCRIPTION

(52) U.S. Cl. **D6/583**

FIG. 1 is a perspective view of a between rounds absorbent
mat for boxing ring showing my new design;

(58) Field of Search D6/582–583, 592;
428/83, 88, 95; 15/215–217; D21/771,
787

FIG. 2 is a rear elevational view thereof;

(56) **References Cited**

FIG. 3 is a front elevational view thereof;

U.S. PATENT DOCUMENTS

FIG. 4 is a side elevational view thereof, the elevational
view of the opposite side being a mirror image thereof;

1,865,459 A 7/1932 Edmands
3,083,393 A * 4/1963 Nappi 15/215
3,228,491 A 1/1966 Gatsos
D253,985 S * 1/1980 Bond D6/583
D270,801 S * 10/1983 Curatolo D6/583
